PIVOTED BREECH BOLT LOCK

Bernard Maillard, Geneva, Switzerland, assignor
to the Society "Brevets Aero-Mecaniques"
S. A., Geneva, Switzerland, a society of Swit-
zerland

Application December 24, 1947, Serial No. 793,734
In Switzerland July 14, 1945

Section 1, Public Law 690, August 8, 1946
Patent expires July 14, 1965

5 Claims. (Cl. 89—190)

1

Some automatic firearms include a breech block moving inside a breech box and a locking device for securing the breech block to the breech box when a shot is fired. Locking of the breech block is generally ensured by a locking member which cooperates with the breech box. Unlocking of the breech block, after firing of a shot, is obtained through a control device including movable parts which act upon the locking member and are operated, for instance, by one or several pistons pushed backward by the powder gases from the gun barrel. The movable parts are generally constituted by one or several sliding pieces disposed laterally of the breech block and movable with respect to both the breech block and the breech box. The center of gravity of the breech block and the point where said breech block bears against the locking member are generally located in eccentric positions with respect to the gun barrel axis such that the breech block is subjected, when a shot is fired and during the unlocking operation that follows, to a rocking torque which creates reactions between the breech block and the breech box. If, as it is the case in the constructions used up to this time, at least a portion of these reactions is transmitted from the breech block to the breech box through the movable parts of the unlocking device, these parts are called upon to overcome a considerable resistance in the course of their displacements for unlocking the breech block. This is due to the fact that in this case the wedging and frictional stresses produced by said rocking torque uselessly absorb a considerable amount of energy and create risks of jamming of these parts.

The object of the present invention is to eliminate these drawbacks. The system according to my invention includes a breech block movable inside a breech box, a locking device for securing the breech block to the breech box when a shot is fired and a control device for unlocking or releasing the breech block after firing of this shot, this control device including sliding pieces movable longitudinally inside a housing provided between the breech block and the breech box. According to my invention, the breech block and the breech box are provided with surfaces adapted to cooperate together to oppose the tendency to rocking of the breech block under the effect of the reactions caused by the firing of the shot, whereby the control device sliding pieces located in the housing between the breech block and the breech box do not undergo any wedging stress and keep the degree of freedom necessary for their good operation.

2

A preferred embodiment of my invention will be hereinafter described with reference to the accompanying drawings given merely by way of example and in which:

- Fig. 1 is a longitudinal elevational section on the line I—I of Fig. 2;
- Fig. 2 is a horizontal longitudinal section;
- Fig. 3 is a sectional view on the line III—III of Fig. 2;
- Fig. 4 is a perspective view on a larger scale of the breech system.
- The breech block 11 is movable longitudinally in a breech box 12 and can be locked with respect thereto by means of a locking member 13 adapted to bear through an oblique surface 14 on a cross piece 15 fixed with respect to said breech box. The breech box is rigid with a barrel 16 including a cartridge chamber 17. The movable parts of the unlocking device include two lateral sliding pieces 21 each provided with a recess 20 and a transverse bar 22 extending between said sliding pieces and connecting them with a firing pin 27. The front ends of sliding pieces 21 are in contact with two pistons 23 movable in cylinders 24 parallel to the barrel axis and in communication with the inside of said barrel. Firing pin 27 is subjected to the action of an axial spring 25 and two lateral springs 26 are interposed between sliding pieces 21 and breech block 11.
- Sliding pieces 21 bear, through their lower faces 31, upon surfaces 32 of breech block 11 and, through their upper faces 33, against surfaces 34 of breech box 12. The breech block is guided in the breech box, at the bottom, through direct contact with guiding surfaces 30 of the breech box and at the top, indirectly, through sliding pieces 21 the upper faces 33 of which are, as just above mentioned, guided along corresponding surfaces 34 of breech box 12. However, in the locking position, the breech block is directly and positively connected with the breech box owing to the provision in the front part of said breech box of recesses 29 in which the front ends of parts 32 are engaged. Thus, the rocking torque applied to the breech block is directly transmitted to the breech box from the time the shot is fired until the end of the unlocking period. This prevents any possibility of wedging of sliding pieces 21 between breech block 11 and breech box 12 for, when the breech block and the breech box are engaged together (the ends of parts 32 being inserted in recesses 29), a certain play is left between the sliding pieces and the breech box, which play permits an easier dis-

placement of the sliding pieces to ensure unlocking.

The system works in the following manner. Immediately before firing, the parts are in the position shown by the drawing, that is to say the breech block 11 is locked in forward position by the fact that each locking member 13 bears through its face 14 against bolt 15 and is maintained in this position by the corresponding sliding piece 21 which keeps said member 13 applied downwardly.

When the shot is fired, breech block 11 is subjected, at the front, to the action of the rearward force exerted by the powder gases from cartridge chamber 17, this force passing above the center of gravity of said breech block, and, at the rear to the effect of the frontward reaction force exerted by locking member 13, this reaction passing below said center of gravity. The couple formed by these two forces tends to rock breech block 11 so as to lift the front part thereof. This rocking torque is opposed by the reaction of the surfaces 29 of breech box 12, under which the front ends of the surfaces 32 of breech block 11 are engaged.

A very short time after the shot is fired, pistons 23 are pushed rearwardly by the pressure of the powder gases in the barrel. They transmit this rearward movement to sliding pieces 21. As soon as the recesses 20 of said pieces 21 come above locking members 13, these members become free to pivot upwardly about their front ends engaged in cylindrical bearings 28 of breech block 11. Due to the obliquity of surface 14, locking members 13 pivot upwardly to pass upon piece 15 under the effect of the reaction exerted by said piece. This unlocks breech block 11, which can now slide rearwardly under the effect of the pressure of the gases from cartridge chamber 17. Breech block 11 moves together with sliding pieces 21 which guide it through their upper faces 33 in breech box 12.

Cooperating surfaces 29 and 32 are in engagement only when the breech block is locked at the front part of the breech box and during the unlocking period. They permit a satisfactory working of the unlocking sliding pieces 21 which no longer risk being wedged during their operation by the rocking torque above referred to.

In a general manner, while I have, in the above description, disclosed what I deem to be practical and efficient embodiments of my invention, it should be well understood that I do not wish to be limited thereto as there might be changes made in the arrangement, disposition and form of the parts without departing from the principle of the present invention as comprehended within the scope of the accompanying claims.

What I claim is:

1. In an automatic firearm, the combination of a breech box provided with a housing, a breech block slideable in said housing, means for locking said breech block with respect to said breech box, a control device for unlocking said breech block after a shot is fired, said control device including longitudinally slideable pieces located between said breech block and said breech box, said breech box being provided in

the front wall of said housing with elongated recesses extending in the direction of movement of said breech block and projections at the front end of said breech block arranged to engage said recesses in the locked position of the parts to oppose rocking of said breech block upon firing of a shot, whereby said slideable pieces are protected against wedging stresses caused by said rocking.

5 10 15 20 25 30 35 40 45 50 55 60 65

2. A combination according to claim 1 in which said projections are disposed laterally with respect to said breech block.

3. In an automatic fire arm, the combination of two breech elements, to wit a breech box provided with a housing and a breech block slideable in said housing, means for locking said breech block in front position with respect to said breech box, a control device for unlocking said breech block after a shot is fired, one of said breech elements being provided in its front part with elongated recesses extending in the direction of movement of said breech block, and projections at the front end of the other breech element arranged to engage said recesses in the locked position of said breech block to oppose tendency thereof to rocking upon firing of a shot.

4. In an automatic fire arm, the combination of two breech elements, to wit a breech box provided with a housing and a breech block slideable in said housing, means for locking said breech block in front position with respect to said breech box, a control device for unlocking said breech block after a shot is fired, said control device including longitudinally slideable pieces located between said breech block and said breech box, one of said breech elements being provided in its front part with elongated recesses extending in the direction of movement of said breech block, and projections at the front end of the other breech element arranged to engage said recesses in the locked position of said breech block to oppose tendency thereof to rocking upon firing of a shot, whereby said slideable pieces are protected against wedging stresses caused by said rocking tendency.

5. In an automatic fire arm, the combination of a breech box provided with a housing and a breech block slideable in said housing, means for locking said breech block with respect to said breech box, a control device for unlocking said breech block after a shot is fired, said breech box being provided in its front wall of said housing with elongated recesses extending in the direction of movement of said breech block, and projections at the front end of said breech block arranged to engage said recesses in the locked position of said breech block to oppose tendency thereof to rocking upon firing of a shot.
